(57) **CLAIM**

The ornamental design for an aerosol generation device, as shown and described.

DESCRIPTION

FIG. 1 is a front perspective view of the aerosol generation device showing the device when the aerosol opening is open;

FIG. 2 is a front perspective View showing the device when the aerosol opening is closed;

FIG. 3 is a rear View thereof;

FIG. 4 is a front View thereof;

FIG. 5 is a right side View thereof;

FIG. 6 is a left side View thereof;

FIG. 7 is a top View thereof; and,

FIG. 8 is a bottom View thereof.

In the drawings, the broken lines represent portions of the aerosol generation device that form no part of the claimed design.
